AWARD TROPHY

William A. Borba, South San Francisco, Calif.

Application July 16, 1949, Serial No. 3,954

Term of patent 7 years

(Cl. D29—23)

To all whom it may concern:

Be it known that I, William A. Borba, a citizen of the United States of America, residing at 524 Spruce Avenue, South San Francisco, California, have invented a new, original, and ornamental Design for an Award Trophy, of which the following is a specification, reference being had to the accompanying drawing, forming part thereof, wherein,

Fig. 1 is a view in front elevation of an award trophy embodying my new design; and

Fig. 2 is a view in side elevation thereof.

The dominant features of my design reside in the portions shown in full lines.

I claim:

The ornamental design for an award trophy, substantially as shown and described.

WILLIAM A. BORBA.
